US00D689794S

(12) **United States Design Patent**
Bracy et al.

(10) **Patent No.:** **US D689,794 S**
(45) **Date of Patent:** **** Sep. 17, 2013**

(54) **THREE WHEELED VEHICLE**

(75) Inventors: **Garth H. Bracy**, Long Lake, MN (US);
Gurminder Singh Bhandal, Pasadena, CA (US); **Gregory C. Brew**, Minnetonka, MN (US)

(73) Assignee: **Polaris Industries Inc.**, Medina, MN (US)

(**) Term: **14 Years**

(21) Appl. No.: **29/387,929**

(22) Filed: **Mar. 21, 2011**

(51) **LOC (9) Cl.** **12-08**

(52) **U.S. Cl.**

USPC **D12/85**

(58) **Field of Classification Search**

USPC D12/85, 86, 131, 107; D21/424, D21/433, 434; 180/65.1, 210; 296/181.1, 296/181.5
